UNITED STATES PATENT OFFICE.

DANIEL PRESCOTT MOWRY, OF MONTREAL, QUEBEC, CANADA.

DESIGN FOR A TOOTHBRUSH.

Application filed November 16, 1927. Serial No. 24,141. Term of patent 14 years.

To all whom it may concern:

Be it known that I, DANIEL PRESCOTT MOWRY, a citizen of the United States of America, and residing in the city of Montreal, in the Province of Quebec, in the Dominion of Canada, have invented a new, original, and ornamental Design for Toothbrushes, of which the following is a specification, reference being had to the accompanying drawings, forming part thereof.

In the drawings Figure 1 is a perspective view and Figure 2 is a front elevational view of my tooth brush.

I claim:

The ornamental design for a toothbrush as shown.

DANIEL PRESCOTT MOWRY.
